OR

D 13,413

EX

No. 13,413

Nov. 14, 1882

UNITED STATES PATENT OFFICE.

JOHN L. POPE, OF CLEVELAND, OHIO.

DESIGN FOR A WEAR-IRON.

SPECIFICATION forming part of Design No. 13,413, dated November 14, 1882.

Application filed August 2, 1882. Term of patent 14 years.

To all whom it may concern:

Be it known that I, JOHN L. POPE, of Cleveland, in the county of Cuyahoga and State of Ohio, have invented and produced a new and original Design for Wear-Irons, of which the following is a specification, reference being had to the accompanying engraving, forming part thereof.

This invention of mine relates to a design for wear-irons employed in connection with carriages and other vehicles; and it consists, first, of the general shape of the article; and, secondly, in certain features of ornamentation, all as will be hereinafter more particularly described.

In the engraving which accompanies this specification the upper portion of the wear-iron, it will be seen, has a peculiar shape—namely, that of a triangle—which shape, so far as my knowledge extends, is novel as applied to wear-irons, and certainly presents to the eye of the beholder a neat and handsome appearance. Two of the sides, *a* *b*, composing this triangular figure I have made curved or bowed, thereby increasing the beauty of the article. I have adorned the iron with a rib or bead, which will be found designated by the letter *c*. The lower portion, *d*, of the iron I have made rectangular, and have perforated 30 with round holes, as seen, at which point the

article is attached to the carriage or other vehicle, as customary. Between this lower portion, *d*, and the sides *a* and *b* of the triangle I have cut out the metal of the iron in artistic form to further increase the beautiful 35 appearance of the article.

What I claim as of my invention, and desire to secure by Design Letters Patent, is—

1. A wear-iron made triangular in shape at its upper portion, as shown. 40
2. A wear-iron made triangular in shape at its upper portion, and having its two sides *a* and *b* curved or bowed, substantially as shown.
3. A wear-iron with a triangular upper portion ornamented with a rib or bead, *c*, substantially as shown. 45
4. A wear-iron with a triangular upper portion and a rectangular lower portion, substantially as shown.
5. A wear-iron with a triangular upper portion and a rectangular lower portion, and having the opening between them of substantially the form shown. 50

In testimony whereof I have hereunto set my hand this 22d day of June, 1882.

JOHN L. POPE.

In presence of—

CHAS. W. MOSES,
C. M. COPP.
